UNITED STATES PATENT OFFICE

1,990,356

HEATER

Reuben N. Trane, La Crosse, Wis.

Application March 31, 1933, Serial No. 663,707

3 Claims. (Cl. 257—137)

My invention relates to a heater for buildings wherein outside air is ventilated into the building and is heated or air conditioned before entering the rooms.

5 One of the objects of my invention is the elimination of drafts resulting from ventilating into the room air that is too cold.

Another object of my invention is the elimination of overheating resulting from ventilating 10 into the room air that is too warm.

Another of the objects of my invention is the distribution of the heat evenly across the heater.

The various features of novelty which characterize my invention are pointed out in claims annexed to and forming a part of this specification.

In the accompanying drawing which illustrates my invention, Figure 1 is a perspective view of the air conditioning unit, with a portion of the enclosure broken away to show the heater and valve, and with a portion of the heater broken away to show the outlets into the opposite header of the heater.

Figure 2 shows the valve in elevation, partly in section, with a portion of the valve body broken away.

Figure 3 is a side elevation of the heating element.

Figure 4 is a transverse section of the header taken on the line A—A of Figure 3.

30 Figure 5 is a transverse section of the return header taken on the line B—B of Figure 3.

Referring to Figure 1 of the specification, 10 represents the housing of the unit with an outlet 12, a recirculated air inlet 11, and an outside inlet 13. 14 represents the blower operated by the motor 15 and discharging air upward through the fan outlet 16. 17 represents the heater which is shown more in detail in Figures 3, 4 and 5.

In Figure 3, 18 is the inlet header, 19 the outlet header, said headers being connected by heat tubes 20, on which are mounted fins 21. The fins comprise thin metallic sheets with apertures 22 therein. The fins are mounted on the heat tubes by passing them through the apertures 22 and engaging the fins in a heat conducting relationship in the conventional way so that the fin over its entire surface may receive heat from any tube. The fins extend across the heater as shown in Figure 1. In the heater a plurality of heat tubes 20 are rolled into the side walls 23 and 24 of the headers 18 and 19 respectively, and form connecting mediums between said headers. In the header 18 the tubes 20, with the exception of tube 25, have an orificed bushing 26, while in the header 19 the ends of the tubes 20 are open and

only the tube 25 has the orificed bushing. It is understood that the term open is relative and that a ring could be inserted in the opening of the tubes which would not impede the passage of steam, or one orifice may be larger than the other orifices, the limitation being that the larger orifices at the inlet should be of such diameter in comparison to the diameters of the other orifices that all of the tube or tubes with the larger orifices will be substantially filled with steam before steam enters the other tubes in any substantial amount.

In the inlet header 18, the effect of the orificed bushing is to restrict the flow of steam into the tubes 20 with the exception of tube 25, which having no orificed bushing tends to fill with steam before the tubes 20. The effect of the orificed bushing in tube 25 in the outlet header 19 is to restrict the outward flow of steam from tube 25, before it has been condensed, and the orifices in the bushings 26 being of equal diameter tend to equally balance and distribute the pressure. It is manifest that only in the coldest weather is the full capacity of the heater required but that in mild weather, especially above 40° F., it is important to distribute some steam the entire length of the heater; otherwise the end of the heater near the inlet header would be very warm but that portion of the heater near the outlet header would be cold, resulting in failure to heat the incoming air, with resultant cold air drafts.

It is manifest that in the present disclosure that a small amount of steam will heat the tube 25 the entire length. Due to the construction wherein each fin 21 is mounted on each tube, it is also apparent that steam in any tube will tend to heat all of the fins mounted thereon. Thus steam in the tube 25 will impart some heat to the entire surface of all of the fins of the heater. The tube 25 is selected to carry the initial steam supply because it passes through each fin at approximately a middle point, thereby distributing its heat equally on both sides of the tube.

A heater of the kind described is of importance in a unit ventilator where it is designed to have the steam supply to the heater responsive to the outlet temperature of the heater. In this connection it is desirable to have the outlet temperature of the air from the heater at substantially the same temperature over the entire length of the heater, or with a comparatively small gradient from the inlet end to the outlet end.

Pipe 27 supplies steam to the heater through the temperature control valve 28, which is actu-

ated by two bulbs 29 and 30 respectively. The bulb 29 is responsive to the temperature of the air emitting from the heater 17, while the bulb 30 is responsive to the temperature of the air entering the recirculating air inlet 11, or it may be placed outside of the housing entirely and be subject entirely to the temperature of the room air.

Within each bulb is a volatile fluid and the space within each bulb is in communication with the space within the bellows 41 by means of the capillaries or conduits, 31 and 32 respectively, which unite at 33, thence by the capillary 34 entering the valve body through the aperture 35. The operating portion of the valve, with the exception of the two bulbs and capillaries, is similar in construction to the temperature control valve set forth in U. S. Patent No. 1,847,911 dated March 1, 1932, issued to me. On a valve body 38 are mounted bonnets 36 and 37. Within the valve body 38 is the port 39, the throttle 41 actuated by the thermostatic bellows 40, which in turn is actuated by the pressure of the saturated vapor therein, due to the temperature of the volatile liquid in the bulbs 29 and 31 respectively. The bellows 42 operates to balance the thermostatic bellows 40, and within the bellows 42 is a spiral spring 43 acting in opposition to the force of the saturated vapor in the thermostatic bellows 40. 44 is an adjusting screw bearing against the spring 43 for the purpose of adjusting the force of the spring 43. The pressures of the saturated gas within the bellows 41 being determined at the temperature of air surrounding the bulb and at which it is desired that the valve open or close, the spring is adjusted to equal that pressure. Any decrease in the pressure of the saturated gas will cause the valve to open due to the force of the spring 43. The vapor pressure within the bellows 40 is responsive to the liquids in the bulbs 29 and 30.

The temperature of the air surrounding each bulb will have an influence upon the pressure of the saturated vapor, and a change in the temperature of the air surrounding each bulb will tend to either raise or lower the pressure of the saturated vapor in the bellows 40 and actuate the valve.

In the invention disclosed, the applicant prefers to place one bulb 29 in the air from the heater, preferably near the outlet header where there is a minimum amount of heat transfer to the incoming air, and one bulb in the room air or in the recirculating air inlet. If the valve is adjusted to close at 67° and to open when the temperature falls to lower than 67°, then whenever the outlet air from the heater is less than 67°, the valve will open, pass steam into the heater which will heat the ventilated air. By adjusting the forces within the valve, sufficient differential in vapor pressure will be produced by only a few degrees change in temperature to open the valve sufficiently. It is manifest that under this arrangement no air will be ventilated into the room at substantially less than 67°.

The other bulb 30 is located in the room air or

in the recirculating air inlet. If, for example, the valve is set at 67°, as above described, any decrease in the temperature of the air surrounding bulb 30 will also open the valve and supply sufficient steam to the heater to maintain the temperature of the air surrounding the bulb 30 at substantially 67°. If, during this operation, the outlet air from the heater would increase substantially above 67°, it would only momentarily effect the valve because the liquid 29 would transfer to the bulb 30 and would be inoperative until the temperature of the air surrounding the bulb 29 was reduced to substantially the temperature of the air surrounding bulb 30, where condensation would take place within the bulb 29 and it would again become operative.

It is manifest with the heater designed as described and the valve constructed as described that the ventilating unit will regulate the minimum temperature of the incoming ventilated air and will regulate the minimum room temperature. With reference to the maximum temperature of the room, when both the inlet air temperature and the room temperature exceed 67°, the valve will close and prevent over-heating due to steam. The temperature setting of 67° is merely given as a convenient example, it being understood that the operator will set the valve at the temperature which will produce the desired air conditions and temperatures.

While I have described in detail a preferred embodiment of my invention, it is understood that I am not limited to the details therein set forth except as defined by the following claims.

I claim:

1. In a heater for air conditioning, the combination of inlet and outlet headers with spaces therein, heat tubes with extended heating surface connecting said spaces, some of the said tubes being provided at their inlets with restrictive openings of fixed diameter, the remainder of said tubes being provided at their inlets with restrictive openings of larger fixed diameter, the first named tubes having larger openings of fixed diameter at their outlets than the remainder of said tubes.

2. In a heater for air conditioning, the combination of inlet and outlet headers with spaces therein, heat tubes with extended surface connecting said spaces, some of said heat tubes being provided with restrictive openings of fixed diameter at their inlets and the remainder of said tubes being provided with restrictive openings at their outlets.

3. In a heater for air conditioning, the combination of inlet and outlet headers with spaces therein, heat tubes with extended surface connecting said spaces, at least one of said heat tubes being provided at its inlet with a restrictive opening of fixed diameter, the remainder of said tubes being provided with smaller openings of fixed diameter, said extended surface comprising metal strips mounted upon all of said heat tubes and extending substantially across said heater.

REUBEN N. TRANE.
